UNITED STATES PATENT OFFICE

EMIL J. NIELSEN, OF ROCKFORD, ILLINOIS, ASSIGNOR, BY MESNE ASSIGNMENTS, TO THE SAN-DURO MANUFACTURING CO., OF ROCKFORD, ILLINOIS, A CORPORATION OF ILLINOIS

TOILET SEAT OR COVER HINGE CONSTRUCTION

Application filed September 22, 1926. Serial No. 136,902.

This invention relates to an improved molded toilet seat or cover and is particularly concerned with the novel construction of the hinge arms molded integral with the main body portion of the seat or cover.

One of the principal objects of the invention is to provide, in a novel construction of the character referred to, an especially practical and effective means for reinforcing the hinge arms consisting of hollow perforated metallic inserts about, through and into which the molded material will readily flow and form a bond.

A further object is to provide the inserts in the form of stamped sheet metal parts preferably providing in one piece a shank portion for reinforcing the juncture of the hinge arm and body and a head portion providing a bearing lining within an opening 20 molded in the outer end of the hinge arm for the reception of the hinge pin in the mounting of the seat or cover.

Aside from the advantage as to saving in cost resulting from my improved construction and the advantages of neatness in appearance and practically indestructibility, is to be mentioned the fact that the present construction presents no crevices but has positively flush surfaces at all points so that 30 it may be kept clean readily and there are no metallic parts exposed which would be subject to corrosion or would require frequent polishing to maintain a proper cleanly appearance. In other words, the present 35 construction affords a thoroughly sanitary and extremely durable seat or cover of bakelite material molded in one piece.

The invention is illustrated in the accompanying drawings wherein—

40 Figure 1 is a plan view of a toilet seat constructed in accordance with the present invention with the hinge arms molded integral with the main body portion of the seat. One of the arms appears in horizontal section;

45 Fig. 2 is a vertical cross section taken on the line 2—2 of Fig. 1;

Fig. 3 is a section similar to Fig. 2 showing the construction in the case of the cover.

Throughout the views, similar reference 50 numerals are applied to corresponding parts.

Toilet seats and covers have usually been provided of wood with varnish or enamel finishes. These finishes first of all soon show evidences of wear and the seats are caused to present a cheap, drab, and unattractive 55 appearance sometimes very much out of keeping with otherwise expensive and elaborate toilet fixtures. Consequently the refinishing of a toilet seat or cover was frequently necessary and was, of course, both 60 unhandy and inconvenient. The finishes are furthermore hard to keep clean and in a sanitary condition and are subject to peeling, cracking and chipping off and, as a result, 65 often present rough surfaces. Acids and alkalies coming in contact with the seats under service conditions attack the finish and ruin the appearance of the seats. Furthermore, wooden seats absorb moisture readily 70 and often become moisture logged and, as a consequence, open at the joints. It also frequently happens that the seats rot at the 75 hinges which results in the seat becoming extremely loose. There is also the disadvantage, as regards the hinge connection, that these have usually been nickel plated and, 80 as a result, require frequent polishing if any semblance of cleanliness is to be maintained because the finish is quickly attacked by alkalies and acids coming in contact therewith. For example, lye and other disinfectants and 85 deodorants will readily attack the nickel plating. At any rate, the plated fittings soon show evidences of corrosion and it is common experience to find heavy verdigris coatings on these parts.

The present invention avoids the above 90 enumerated objections to wooden toilet seats and covers by molding the same of bakelite material preferably with the hinge arms molded integral with the main body portion of the seat or cover as herein illustrated. The chemical and physical characteristics of this material are particularly suited for this 95 use as it is unaffected by acids or alkalies, does not absorb moisture and is generally thoroughly sanitary and extremely durable. It never shows evidences of wear and is not readily scratched, dented or otherwise marred. Neither will it crack or break if 100

subjected to rough usage. It presents a smooth, flush surface without joints even at the hinge arms because the entire seat, including the hinge arms, is molded in one piece; it submits itself to easy cleaning and 5 maintains a definite gloss and lustre without the need for considerable polishing. The appearance presented is that of a quality product first and last and one which will harmonize properly with the highest grade toilet fixtures. Its very sanitary and extremely durable character causes it to make an especial appeal for use in hotels and other public buildings as well as for use in homes.

10 The toilet seat, indicated by the reference numeral 5, and the toilet seat cover 6 are formed of bakelite material each molded in one piece preferably with the hinge arms 7 and 7' molded integral with the main body portion of the seat and cover respectively.

15 The under side of the seat, and of the cover as well, is formed with elongated cavities, as shown at 8 and 8' with a view principally to a saving in molding material as the constituents of bakelite are fairly expensive.

20 Furthermore, this method of construction makes possible an appreciable reduction in weight without sacrificing the requisite strength. Intermediate reinforcing webs between the cavities afford additional strength and also provide a convenient place for mounting buffer pads. Obviously, the construction of the hinge arms molded integral with the main body portions of the seat and cover is desirable, not only from 25 the standpoint of the saving in cost which results therefrom, but also from the standpoint that no crevices are formed anywhere and everything presents flush surfaces easy 30 to be kept clean.

40 As shown in Fig. 2, the hinge arms 7 are reinforced by a hollow perforated metallic insert 9, providing a shank portion 10 to reinforce the juncture between the arm and the main body portion, and a head portion 11 to provide a bearing lining for the opening 12 molded in the outer end of the hinge arm for reception of the hinge pin in the mounting of the seat. As illustrated, the insert 9 45 is preferably formed from a single piece of sheet metal, the shank portion 9 being cut away as shown at 13, and provided with a plurality of perforations, as indicated at 14, the general form of the shank portion being tubular so that the bakelite in molding will flow into the center as well as about all sides of the shank portion. The cut out portions 50 13 and perforations 14 further permit the molded material to flow into these places and form a perfect bond between the bakelite and the metal insert. The head portion 11 55 is looped to form part of a ring-shaped bearing lining within the opening 12. The lining extends approximately 240° within the opening 12 so that a proper bearing is afforded by

the hinge pin arranged to be engaged therein when the seat is mounted on the toilet bowl. Obviously, the construction is thoroughly practical and extremely durable. Due to the reinforcement, the hinge arms are practically indestructibly joined with the main body portion of the seat. If desired, the hinge arms may be formed with slight cavities adjacent the juncture with the main body portion of the seat, as shown at 15, which 70 gives an ornamental effect without lessening the strength of the parts, and at the same time results in a slight saving in material. 75

80 The construction just described is followed in the case of the cover, as appears in Fig. 3. The only modification in this construction lies in the curving of the shank portion 10 of the insert 9 to follow the curvature of the hinge arm 7'. The construction is otherwise identical with that shown in Fig. 2. 85

I claim:

1. In a toilet seat or cover comprising a main body portion of molded material, a projecting supporting arm for hingedly mounting said body, said arm being molded integral with said body and of the same material and having an insert molded therein formed of one elongated piece of sheet metal bent to bring the ends together to provide a shank portion for reinforcing the juncture of the 90 arm and body, the said piece of sheet metal being conformed in a loop at the place of bending to provide a bearing lining within an opening provided in the outer end of said arm for the reception of a hinge pin in the 95 mounting of said seat or cover.

2. A structure as set forth in claim 1 wherein in the sheet metal insert has the end portions thereof bent to channel form to make the shank rigid and thus further reinforce the 100 juncture of the arm and the body.

3. In a toilet seat or cover comprising a main body portion of molded material, a projecting supporting arm for hingedly mounting said body, said arm being molded integral with said body and of the same material and having an insert molded therein formed of a strip of sheet metal bent to provide a loop to serve as a bearing lining within an opening provided in the outer end of 110 said arm for the reception of a hinge pin in the mounting of said seat or cover, the said piece of sheet metal having the rest thereof providing a shank portion imbedded in and reinforcing the juncture of the arm and body. 115

4. A structure as set forth in claim 3 wherein the shank portion of said insert is bent to provide at least one longitudinally extending reinforcing rib whereby the insert is rendered rigid properly to reinforce the juncture of the arm and body, the said insert being also perforated to imbed solidly in the material of the seat in molding to give the desired strength.

5. A structure as set forth in claim 3

wherein the shank portion of said insert is bent to provide at least one longitudinally extending reenforcing rib whereby the insert is rendered rigid properly to reenforce the juncture of the arm and body.

5 6. In a toilet seat or cover comprising a main body portion of molded material having a projecting supporting arm for hinged-
10 ly mounting said body molded integral therewith, said arm having an opening provided in the outer end thereof for the reception of a hinge pin in the mounting of said seat or cover, an insert molded in the body and arm, said insert being in the form of a unitary structure having a shank portion im-
15 bedded in and reenforcing the juncture of the arm and body, and a tubular head portion imbedded in the opening in the arm whereby to serve both as a reenforcement for the outer end of the arm and as a bearing lining for said opening.

7. A device of the character described comprising a body formed of a plastic material, a hinge arm having a portion inserted in said body, said arm projecting from the body for supporting the same, the plastic material of the body extending outwardly therefrom over the projecting portion of said arm and entirely covering the outside thereof, said arm having the outer end thereof constructed for cooperation with a support for the body with relation to which the body is arranged to have pivotal movement.

8. A device of the character described comprising a body formed of a plastic material, a hinge arm having a portion inserted in said body, said arm projecting from the body for supporting the same, the outer end of said arm having an opening provided therein adapted to receive a hinge pin, the plastic material of the body extending outwardly from the body over said arm and completely covering the outside thereof but leaving the opening in the outer end clear for entry of the hinge pin therein.

9. A device of the character described comprising a body formed of a plastic material, a hinge arm having a portion inserted in said body, said arm projecting from the body for supporting the same, the outer end of said arm having an opening extending therethrough adapted to receive a hinge pin for pivotal support of the body, the plastic material of the body extending outwardly from the body over said arm and completely covering the outside thereof including the portions thereof at the ends of the opening but leaving the opening clear for entry of the hinge pin therethrough.

60 In witness of the foregoing I affix my signature.

EMIL J. NIELSEN.
